FIG. 1

FIG. 2

FIG. 3

FIG. 4

FIG. 5

FIG. 6

FIGURE 1 is a top perspective view of a case for beverage bottles or the like, showing my new design;

FIGURE 2 is a side view thereof;

FIGURE 3 is a longitudinal section taken along the line 3—3 of FIGURE 5;

FIGURE 4 is a front or rear view;

FIGURE 5 is a top plan view thereof; and

FIGURE 6 is a bottom plan view thereof.

Specifically, the beverage bottle case comprises in combination trapezoidal-shaped hand openings set within a smooth-sided case, elongated rectangular recesses in the end panels over the hand openings, and a base plate as illustrated in FIGURES 5 and 6.

I claim:

The ornamental design for a case for beverage bottles or the like, as shown and described.
